UNITED STATES PATENT OFFICE

147,335

DESIGN FOR A FOG LAMP FOR
AUTOMOBILES

George C. Knight, Detroit, Mich.

Application April 25, 1946, Serial No. 128,957

Term of patent 7 years

(Cl. D48—32)

To all whom it may concern:

Be it known that I, George C. Knight, a citizen of the United States, residing at Detroit, in the county of Wayne and State of Michigan, have invented a new, original, and ornamental Design for a Fog Lamp for Automobiles, of which the following is a specification, reference being had to the accompanying drawings, forming a part thereof, and wherein:

Fig. 1 is a top plan view of a fog lamp for automobiles, showing my new design.

Figs. 2 and 3 are respectively back and side elevational views thereof.

I claim:

The ornamental design for a fog lamp for automobiles, as shown.

GEORGE C. KNIGHT.
